UNITED STATES PATENT OFFICE.

CHARLES R. SAATWEBER, OF PATERSON, NEW JERSEY, ASSIGNOR OF ONE-HALF TO GEORGE W. RENKEL, OF SAME PLACE.

LOOM-BEAM ATTACHMENT.

SPECIFICATION forming part of Letters Patent No. 662,029, dated November 20, 1900.

Application filed October 7, 1899. Serial No. 732,912. (No model.)

To all whom it may concern:

Be it known that I, CHARLES R. SAATWEBER, a citizen of the United States, residing at 36 Barbour street, Paterson, in the county of Passaic and State of New Jersey, have invented 5 a new and useful Improvement in Loom-Beam Attachments, of which the following is a specification.

My invention relates to improvements in 10 loom-beams in which the tension is self-regulating and the slack warp when drawn back is automatically taken up on the beam and the tension on the warp is always uniform.

The objects of my improvements are, first, 15 to provide a uniform tension on the beam and with a less weight than now used; second, to counteract the sudden slips of the tension when the warp is being drawn off; third, to wind back on the beam automatically the 20 warp when it is found necessary to draw back the warp and to keep all the slack out of the warp; fourth, to keep the same tension on the warp when it is drawn back as when the warp is being drawn off, and, fifth, to keep the warp 25 continually and uniformly unwinding as the goods are woven. I attain these objects by the mechanism illustrated in the accompanying drawings, in which—

Figure 1 is a side elevation of my invention 30 attached to a loom. Fig. 2 is the same as Fig. 1, except that the tension-frame is shown at its lowest point; Fig. 3, a front view of Fig. 2. Fig. 4 is a detail view of the tension-frame with the roller and weights on it. Fig. 35 5 is a detailed view of a cam with the bands attached, and Fig. 6 is a front view of Fig. 5.

Similar characters refer to similar parts throughout the several views.

The warp-beam, the flanges of which are 40 represented by *a* and the barrel on which the warp is wound by *b*, is supported in the journals *u* by the uprights *b*. The tension-frame *d*, as shown in Fig. 4, is also supported in the uprights *b* by the rod *t*. (See Figs. 1 45 and 2.) In the hole *j* a spring *i* is fastened, and the band *p* passes from the spring over the groove in the flange *a* and the other end is fastened in the hole *z* in the frame *d*. The 50 distance from the supporting-rod *t* to the hole *j* is less than from *t* to *z*. The purpose of this will be shown later.

Below the tension-bracket *d*, held in place by the same uprights, are two cams *c*, one on each side of the frame, a detail of which is shown in Figs. 5 and 6. These cams have a 55 hub or cylindrical piece *g* on one side with a groove *4* in the same, in which is fastened and over which is wrapped a band *o*, connected to the one end of the spring *k*, and the other end of the spring is secured by a screw-eye to 60 the uprights *b*. Around the outside or face of the cam *c* is fastened and wrapped for a distance the strap or band *f*, the other end of which is fastened to the tension-frame in the hole 2 or 3, if desired. 65

In the frame *d*, which is about the width of the beam, is a roller *e*, which turns as the warp *u* is drawn from the beam *l* and passes around the roller and then through the loom. The weight *m* rests in the slots *r* in the end 70 of the frame *d*, and the slots are so cut that when the frame is at its highest position, as shown in Fig. 1, the slots will slope inward, so that the weight will slide to a position nearer the center of the frame. The level is 75 shown by line *x*. The distance the frame *d* can be raised and lowered is limited by the pin *v* for the highest point and *w* for the lowest. Both pins are secured to uprights *b*. When the frame *d* rests against the pin *v*, the 80 tension is at its normal or it may be its lowest point. The tension at this point is through the slipping of the band *p*, which is wrapped around the head *a* of the beam. The trouble experienced with the old-style tension is that 85 the beam will remain still at times for several picks of the loom, thus increasing the strain on the silk, sometimes to the breaking-point, and at other times remaining still, as stated heretofore, and then giving a sudden slip 90 more than needed, causing a slack and a consequent bad place woven in the goods, and it is necessary for the weaver to pass around back of the loom and turn the beam back by hand, if necessary to take up any slack or to 95 draw the warp back. The warp *n* should move uniformly with every pitch of the loom and have a uniform tension. If the warp should be drawn back, as is often necessary, the frame *d* would be lowered possibly as far 100 as the pin *w* will permit and the warp will be taken up, some of it by the lowered position

of the roller *e* and part on the beam *a*. When the warp is being drawn from the beam, the upper side of the flange of the beam turns to the left. The frictional contact between the 5 band and the flange has the tendency to draw the roller end of the bracket *d* to its highest point against the pin *v*. When in this position, the spring *i* is under its least tension and the band *p* would then press most lightly on the 10 flange. This is caused by the distance from *s* to *z* being greater than from *s* to *j*. The spring *i* is necessary, as the band *p* would otherwise probably break in case the bracket *d* were drawn to the position shown in Fig. 2, 15 and as the arc passed over by *z* is longer than that passed over by *j* this would tend to increase the tension on the flange of the beam. It will be noticed in Fig. 1 that the weight *m* is at its nearest point to the pivot *t*, and hence 20 exerting its least pull on the lever-bracket *d*. From the aforesaid highest point, if the end of the bracket *d* on which the weight is lowered in any way, by releasing any of the 25 warp from the beam *a* or by drawing back the warp the tension immediately increases on the beam by the sliding of the weight *m* to the other end of the slot *r*, as shown later. When the bracket *d* lowers, the band *p* is tightened and the spring *i* extended, which 30 requires a heavier pull to be made on the warp to cause the band to slip over the flange *a*. When the weighted end of the bracket is caused to lower a certain distance, the slot *r* slopes the reverse way. The weight *m* then 35 slides to the farthest end of the slot *r*, increasing the distance from the weight *m* to the fulcrum *t*, and thus increasing the tension on the band *p*. When the weight end of the bracket lowers, the band *f*, connected to 40 2, permits the cams to turn on the rod *h*, and in so doing the band *f* at its last point of contact is nearer the rod *h* than before. This would cause a slight increase of pull on the band *f* if the pull by the spring *k* on the band 45 *o* remained the same; but as the spring contracts and exerts a less pull on the band *o* by the unwinding of the said band on the hub *g* at the same time the one somewhat equalizes the other and the pull on the band *f* remains 50 nearly the same. When the warp is being

woven or unwound, the bracket *d* is adjusted to a position about horizontal by applying the necessary weights in the slots *r*. With the proper tension now on the warp that tension remains the same, although the bracket 55 raises and lowers, as the warp may unwind irregularly from the beam, at times slipping and sometimes catching. Thus I can get a regular and uniform tension from an irregular unwinding beam. In drawing back the warp 60 the roller *e* and the bracket *d* draws the band *p* and by its friction on the flange *a* turns the warp-beam, and thus winds up some of the warp.

Having thus described my invention, what 65 I claim, and desire to secure by Letters Patent, is—

1. In a self-regulating warp-beam attachment the combination of a warp-beam having grooved flanges *a* and a pivoted tension-bracket containing a roller, the band *p* the 70 spring *i* connected to the said bracket at *z* and *j* respectively, the sloping slots *r* in the bracket *d*, and the weights *m* left free and movable in the slots *r*, as and for the purpose 75 set forth.

2. In a warp-beam attachment, the tension-bracket having the sloping slots *r* and weights movable in the same, and the connecting-points *z* and *j* of the band and spring *i*, said 80 points located to move in unequal arcs, the cam *c* with the spring *k* and the band *o* acting on its hub, and the band *f* connected to its periphery and to the bracket *d* as set forth and described.

3. In a warp-beam attachment, having grooved flanges *a*, the combination of a warp-beam, a pivoted tension-bracket having a band operating in said flanges, the slots *r* in the bracket *d*, the movable weights in the 90 slots and the cam *c* with the band *f* and its hub with its band *o* and spring *k* as set forth and described.

Signed at Paterson, in the county of Passaic and State of New Jersey, this 4th day of October, A. D. 1899.

CHS. R. SAATWEBER.
